Inventor:

Magnum E. Widell

By: Murray, Clark & Felt, Attys.

UNITED STATES PATENT OFFICE.

MAGNUS E. WIDELL, OF CINCINNATI, OHIO, ASSIGNOR TO AMERICAN CAN COMPANY, OF NEW YORK, N. Y., A CORPORATION OF NEW JERSEY.

INTERIOR-COLLAR CAN.

Application filed April 20, 1923. Serial No. 633,366.

The present invention relates to containers of the type in which a separate band, or neck member, is positioned in the upper part of the container body, providing a part upon which a severed body portion, or cover member, may be positioned as a temporary closure after removal from permanent connection with the body.

5 In the ordinary container of this general type, a flange of considerable width is left after removal of the cover part, and this flange engages a considerable area of the exterior of the collar when said part is positioned as a temporary closure. When the 10 container is used for paint, or like sticky substances, it has been found that a serious difficulty arises, due to such contents getting between the cover flange and collar, thus rendering it difficult, if not impossible, 15 to remove the cover.

A principal object of this invention is the provision of a container of the general type referred to in which the temporary, or re-closure member, will engage the collar 25 only on a single line of contact, thus eliminating the difficulty mentioned.

Other objects and advantages of the invention will be apparent as it is better understood from the following description, which, 30 taken in connection with the accompanying drawings, discloses a preferred embodiment thereof.

Referring to the drawings,

Figure 1 is a side elevation, partially 35 broken away, of a container embodying the principles of my invention;

Fig. 2 is an enlarged detail section through the portion of the upper part of the container showing the tearing strip removed and the cover member in separated relationship; and

Fig. 3 is a partial plan view of the blank employed in the container body.

As thus illustrated, the container comprises a body 21, provided with a permanent bottom end 22 and a top closure 23, which is secured in place by interfolding a flange thereon with a flange on the upper end of the body to form a double seam 24. The 45 top closure is formed with the usual double seaming shoulder extending downward from said flange, which shoulder fits tightly within the top part of the can body. The material of the body is scored beneath the top 50 on lines 25 and 26, which set off a tearing

strip adapted to be torn away to open the container. This strip is scored diagonally, as indicated at 27, whereby the line of tear may be directed back to the lines 25 and 26, in case it should be deflected therefrom. A 60 tongue 28 is provided at one end of the tearing strip, taking off from the cam body adjacent a side seam 29 and being adapted to be engaged by a key, or otherwise, for removal of the strip.

65 A separate band, or collar member, 31 is positioned within the upper part of the body to which it is secured by means of a bead 32 arranged within a groove 33 provided on the interior of the body wall. This 70 groove, in the present instance, is formed by an expanding tool operating within the body and forcing the bead 32 outwardly, with resultant bending of the body material. This, of course, forms a bead 34 on the exterior 75 of the can, which may be clinched upon said bead 32, providing a liquid-tight joint between the collar and body. This latter feature is not claimed herein but in my co-pending application Serial No. 636,519, filed 80 May 4, 1923.

The upper edge of the collar 31 is also beaded in the present instance, as shown at 85 35, to provide a convenient friction contact part for engagement by the severed cover, 85 as a temporary closure, as will later be described. In the illustrated construction this bead or bend 35 is the external friction element of the can body.

It will be noted that the upper score line 90 25 is disposed immediately beneath the seam 24, so that when the tearing strip, which is indicated at 36, in Fig. 1, is removed, there is practically no metal left below said seam for engagement with the outer side of the 95 collar 31. By reference to Fig. 2, it will be seen that the part 37 of the body which remains after removal of the strip, is practically all enclosed within the seam 24. The cover 23 has a shoulder 38 inwardly of the 100 seam 24, adapted to rest upon the bead 35, and a vertical wall part 39 is provided about the periphery of a depressed head portion 41, this wall part being somewhat tapered, as shown set-off inward from the container 105 wall, and adapted to frictionally engage within the bead 35 on a single line of annular contact. In this manner, a temporary closure is provided, which will not be subject to the difficulty heretofore referred to 110

when the container is used for paint or like contents.

Referring now to Fig. 3, the form of the body blank employed may be clearly understood. The seam, throughout the greater part of its length, is of the interfolded, or lock, construction, but the material of the blank is cut away at 42 and merely lapped over the opposing edge, as shown at 43 in Fig. 1, in the area in which the bead 34 is formed. This is for the purpose of facilitating the bending of the metal, which would be very difficult with the thicknesses necessary for the lock seam. An auxiliary lock portion 44 is provided above the cut out area 42 and beneath the tearing strip. It will be understood that the portion of the body above said strip is practically all interfolded in the double seam 24 and, therefore, a lock seam in this area is unnecessary.

It results from the above construction that a can is provided having an end member formed with a depressed central portion set off inwardly from the wall of the container and producing an internal friction closure element, and there is also provided a body having means forming an external friction element adapted to receive the friction closure element of the cover. I use the word "external" to describe the surrounding outside friction element and the word "internal" to describe the friction element which is insertable within the external friction element.

Before the parts are assembled the can end in itself has two distinct can-closing means spaced from each other, the first means consisting of a marginal double-seaming flange adapted to be double seamed with the corresponding flange of a can body, and the second means consisting of a central depression spaced inwardly from said flange of the can end and extending downwardly and forming an internal friction closure element to cooperate with a corresponding external friction element of a can body. I consider this can end as a new element of my invention.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages,

the form hereinbefore described being merely a preferred embodiment thereof.

I claim:

1. A container, comprising a body having an end member permanently secured thereto, and a separate collar secured within the upper part of the body, said body being scored beneath the top opposite to said collar to provide a tearing strip adapted to be removed to open the container, and said end member having a depressed central portion adapted to frictionally fit within said collar, and a shoulder of larger diameter than said depressed central portion which fits tightly within the mouth of the can body.

2. A container, comprising a body having an end member fitted therein and permanently secured thereto, and a separate collar secured within the upper part of the body and having an inwardly extending bead at the upper edge thereof, said body being scored beneath the top opposite to said collar to provide a tearing strip adapted to be removed to open the container, and said end member having a depressed central portion adapted to frictionally fit within said collar bead.

3. A can comprising a body and a cover double seamed to said body, the cover having the usual countersink adjacent the double seam, and having in said countersink another depression of less diameter than said countersink and forming a wall to produce an internal friction closure element, and the can body having score lines around the same setting off a tearing strip adjacent the double seam, and the body being provided with means forming an external friction element adapted to receive the said friction closure element of the cover.

4. A can end having two distinct can closing portions spaced horizontally from each other, the first portion consisting of a marginal double seaming flange adapted to be double seamed with a can body, and the second portion consisting of a central depression spaced inwardly away from said flange and extending downward and forming an internal friction closure element to cooperate with a corresponding external friction element of a can body, and a double seaming shoulder of larger diameter than said central depression.

MAGNUS E. WIDELL.
